UNITED STATES PATENT OFFICE.

JACOB E. NEAHR, OF HARTSDALE, NEW YORK.

MATCH SAFE.

Application filed November 28, 1922. Serial No. 603,767.

To all whom it may concern:

Be it known that I, JACOB E. NEAHR, a citizen of the United States, residing in Hartsdale, in the county of Westchester and State of New York, have invented certain new and useful Improvements in Match Safes, of which the following is a specification.

This invention relates to the construction of pocket and other manipulable closed match-safes.

Safes of this type are usually provided with lids or covers, opened to permit introduction of matches, and closed to keep them dry and safe. The covers are usually removable, and are apt to become bent or injured in frequent use, and are sometimes lost.

A feature of the present improvements is a provision whereby matches may be removed singly from the match-safe without opening the cover, by shaking or tapping the box when it is held in an upright or inclined position. The matches may come out through a small hole in the bottom of the box. Another feature of the invention is the provision of means within the box for preventing the matches from packing or choking in a manner to prevent any of them from escaping, and for preventing the matches from assuming a criss-cross relationship near such discharge opening. Said device is in the nature of an upright wall, partition or baffle, which extends from the vicinity of the discharging point, to or towards the back of the match-safe, and divides the safe into right and left compartments, and tends to separate the matches and guide them singly towards and into a vertical channel or chute, which terminates in the discharge orifice.

In some cases the partition may be fixed, but preferably it swings from side to side, thereby improving its efficiency in bringing the matches into orderly arrangement. Moreover, when using a swinging partition, leaf or separator, the special match chute formed in the side of the safe may be omitted, because the edge of the movable par-

tition or leaf may sweep closely to the inner face of the match-safe, and co-operate therewith to form a match-trough or chute for guiding the matches to the discharge orifice.

The match-safe may have at one end a cover or lid, preferably hinged thereto and containing the discharge orifice and a closure therefor. The safe may also have at the other end a hinged lid, having an aperture through which to strike a match either upon a roughened closed end of the match-safe, or upon an ignition strip which is held upon said closed end by means of a lid or cover. The match-safe may be provided with a magazine portion to receive zigzag folds of the ignition strip, which may be pulled out, as required, from time to time.

Other features and advantages will hereinafter appear.

In the accompanying drawings,

Figure 1 is a front elevation of a pocket match-safe, embodying the present improvements in one form.

Figure 2 is a sectional plan of the match-safe, showing the latter in cumbent position, the matches occupying the compartments, one of the matches lying in the discharge chute.

Figure 3 is a view of the bottom of the box, showing the discharge orifice and means for closing the same.

Figure 4 is a sectional side elevation of the match-safe seen at Figure 1.

Figures 5 and 6 show a cylindrical match-safe for table or mantel use, Figure 5 being a cross-section and Figure 6 a vertical section.

Figures 7 to 16 show the match-safe in another form, having a swinging separator or leaf and also a supply of ignition strip in a magazine.

Figure 7 is a sectional elevation of the safe. This view is taken at about the line 7—7 of Figure 8.

Figure 8 is a plan of the cover.

Figure 9 is a plan with the cover removed.

Figure 10 is a transverse section through the safe, taken at about the line 10—10 of Figure 7.

Figure 11 is a perspective view of the apertured cover seen at Figure 8.

Figure 12 is a perspective view of a lining or interior box secured within the safe.

5 Figure 13 is an edge view of the safe with the hinged lids thereon.

Figure 14 is a perspective view of the safe with one of the covers open, and illustrating the manner of arranging the ignition 10 strip on the end of the safe, preparatory to securing it by means of the cover.

Figure 15 is a sectional view of the safe taken at about the line 15—15 of Figure 7.

15 Figure 16 is a perspective view of the bottom cover of the safe.

Figures 17 to 23 are views of the safe in its preferred form.

Figure 17 is a sectional elevation.

20 Figure 18 is a perspective view of the body of the match-safe.

Figure 19 is a perspective view of a top permanently fixed in the match-safe.

Figure 20 is a cross-sectional plan of the closed safe.

25 Figure 21 is a perspective view of the lining or interior box with the leaf hinged thereto.

Figure 22 is a perspective view of a partition which divides the interior of the safe 30 into a match-compartment and an ignition-strip compartment or magazine.

Figure 23 is a transverse section of the safe.

35 The pocket match-safe is of oval or flat-tened contour, Figures 2 and 3, and comprises front and rear sides 10, 11 and a bottom 12, the latter having a discharge orifice 13. At its top the safe has a cover 14.

Extending from top to bottom of the safe, 40 and preferably formed in one side thereof, is a match-discharging channel or chute 15. The cover is preferably fitted around said chute at 16. When any match in the box occupies said chute, it may drop through 45 the aperture 13, at the lower end of the chute, so that the matches may be discharged one at a time. After a match is withdrawn, the box may be shaken or tapped, to work another match into the chute, whence it may 50 be discharged. The chute has capacity for only a single match.

Within the safe there is fixed a partial partition or wall 17 to serve as a baffle or guide. This may extend from the bottom 55 nearly to the top of the safe, and from the rear 11 toward said chute, but terminating short thereof so as to leave a constricted passage at 18 to permit matches to roll from either compartment into the chute. Said 60 partition or baffle separates or prevents the matches from packing together in the neighborhood of the chute, thus obviating the liability of the matches to prevent one another from discharging. This partition or 65 separator also tends to cause the matches to

extend in a direction approximately parallel with the chute when near the same, so that no great amount of shaking or tapping of the box is necessary for the purpose of ejecting or starting a match therefrom. It is 70 not essential in all cases that the partition extend entirely to the rear side of the safe. The safe being always closed, the matches are kept dry, and a substantial protection is secured under all conditions. 75

In the bottom of the box is preferably inserted an inclined floor 19 upon which the matches stand, its inclination being towards the discharge orifice, and an orifice 20 there-in registering with said discharge orifice 13. 80 The inclined floor tends to cause the matches to gravitate towards the discharge chute when the box is in upright position, and favors the entrance of the matches into said chute. 85

Preferably the discharge orifice 13 is closable by means of a slide 21, preferably in the form of a plate pivoted at 22 to the bottom of the box. This plate is between the bottom 12 and the floor 19, and a portion thereof is exposed through an aperture 23 in said bottom, said exposed portion having a nick 24, so that the plate may be swung to open and closed positions by the use of the thumb nail. At one end the plate has a tongue 25 which is swung to position to close the discharge aperture, while at the other end is a projection 26 which serves as a stop to limit the movement of the plate. The bottom of the box is left flat so that it 95 may stand in erect position. 100

In the form of the invention seen at Figures 5 and 6, a cylindrical safe 27 has a cover 28 provided near one edge with a discharge opening 29, so that the matches may 105 be ejected singly through the top of the box when the latter is held upside down. This safe is provided with a diametrical fixed partition or baffle 30 rising from the bottom thereof and extending from the front portion towards the rear of the safe. Upon its front edge the baffle is provided with divergent wings 31, thus giving the baffle a Y shape in cross-section, Figure 5. These wings tend to prevent the matches from 110 crowding one another in the vicinity of the discharge chute 32, so that they are free to enter such chute and may be easily caused to protrude from the discharge opening, and freely drawn out therefrom. The baffle at 115 Figure 4 may be provided with a similar feature. 120

Another feature of this form of the invention is the provision of an improved match-striking surface. For this purpose 125 there are utilized the channels 33 which are formed at the junction of the chute with the body of the safe at the exterior thereof, there being one such channel on each side of the discharge chute. The metal of the box at 130

these points is finely grooved; preferably in horizontal lines, as at 34, thereby making a rough surface, which is excellent for match-striking. The invention, however, is not limited to the use of a match-striking means of this description; and the remaining features are useful whether provision is made for match-striking or not.

In order to render the safe a convenience for different kinds of matches, there is preferably also provided a means for igniting safety matches, comprising a strip 51, which may overlie the panel 49; and may be held down upon the top of the box by means of a cover or lid, the latter comprising a top 52 and sides 53. Said top has a central lon-

In the form of the invention seen at Figures 7 to 16, the partition or leaf 35 is made swingable for increased efficiency in jogging and straightening out the matches and preventing them from fouling or interfering with one another. This leaf may have at 15 its top and bottom ears 37, 38, Figures 7 and 15, whereby it is pivoted in holes in the match-holder, and permitted to swing from side to side as the match-box is shaken, whereby the matches are jogged from skewed 20 positions to parallel or orderly positions. The matches on one side tend to align themselves parallel with the partition, and they also, by their weight, tend to push the partition against the matches on the other side 25 thereof, whereby the latter are also jogged into parallelism. Hence when any match comes directly into line with the discharge orifice, it lies straight and therefore readily drops out of the match-safe. The leaf or 30 partition at Figure 10 extends from its pivot held down in place by the horizontal portion 90 side across the match-safe and close to the opposite side thereof, so that its free edge 95 portion co-operates to a certain extent with the 95 said opposite side of the match-box to a zigzag strip.

opening the box for the discharge of matches. At Figure 13 the top and bottom lids are shown as hinged at 66, 67, to the match-safe, 40, which, at one edge, is accessible through an opening 40° in the side portion of the lid 55 or bottom. To close this end of the box against moisture, this bottom cover may be closed over up an aperture 45 which is made in the lower side of the box by bending an

ear 46 therefrom to afford a bearing for the leaf pivot 38. A corrugated match-striking surface 47 may be formed in the closed box top 48 for simple friction matches. The corrugations may constitute a depressed panel 49 in the top 48 of the safe. on its bottom edge with left-hand and right-hand guiding channels or ways 69, 70 for the matches to be ejected. When the leaf is swung either to the left as at Figure 23, or to the right, one or other channel 70 or 69 will substantially coincide with the discharge orifice 13 in the match-box, as at 125 130

Figure 23. Right and left hand stops 71, 72 are provided for the leaf 68, to arrest the same with either one channel or the other in register with said orifice. This leaf or separator may be formed with pintles 73, to insert in loops 74, struck in from the side of the box.

A closure in the form of a plate 75 is pivoted at 76 to the end of the box and provided with a slightly projecting knurled edge 77, and formed with an opening 44. Within the oblong, rectangular box 78 forming the body of the match-safe (which box may be gold or silver), is fitted a lining comprising opposite wide sides 79 and a narrow side 80, Figure 21. This lining, which may be made of inferior metal, is forced within the tubular structure or box seen at Figure 18, and at the match-discharging end projects below the edge of the safe 78, as at 81, Figure 17, and the bottom cover 82 of the match-safe closes over this projecting portion 81, said cover being pivoted at 83 at one end to the safe 78, and having a discharge orifice 13 and a closure 75.

At its upper end the safe or body 78 is provided with struck-up loops 84 for the pintles of a hinge 85, whereby top cover 86 is pivoted by its end. The safe 78 and cover may be substantially flush with one another, as at Figure 17. The cover 86 may be provided at its top with cutaway or aperture 87 in which to insert the matches for striking. The matches are struck either upon roughened surface 88 or a match-igniting strip 89. The roughened surface 88 is formed upon a cap 90, which fits down tightly within the safe 78, Figure 17; the bottom edge of the cap resting against the top of the inserted box 79, 80.

The end of the ignition strip 89 is clamped down upon the cap 90 by cover 86; this strip being drawn up from a supply in the form of a zigzag-folded strip 91 which is contained in a magazine at the right-hand side, Figure 17, formed by a vertical metal strip 92, which is bent over at its top to form a plate 93, which is riveted at 94 to the under side of the cap 90.

When the supply or folded strip is to be inserted, the covers 82, 86 are swung back; then a finger-piece 95 on the strip or partition 92 is used for swinging this partition to the left, thus opening the magazine, so that the folded strip of ignition material may be dropped therein; the end of the strip extending out so that it may go down through aperture 96 in the end of cap 90, and fold over a tongue 97 formed at the top of said aperture for the purpose of catching the folded strip and preventing it from being pulled up from out of the magazine with the projecting end of the strip. There may be formed upon the plate 92 a spring tongue

98 having a bent-out tip 99, to form the top of the magazine for confining the ignition strip therein.

Variations may be resorted to within the scope of the invention, and portions of the improvements may be used without others.

Having thus described my invention, I claim:

1. A closed match-safe having at one end an orifice for discharging matches singly, and formed with a discharge chute leading to said orifice, and provided with an internal separator adjacent to said orifice, said separator provided with divergent lips tending to prevent the matches from crowding one another in the vicinity of the discharge chute.

2. A closed pocket match-safe having at one end an aperture for discharging matches singly, and having an interior swinging partition hinged at one edge, said partition at its free edge extending to said aperture and preventing the matches from crossing or fouling one another.

3. A closed pocket match-safe having at one end an aperture for discharging matches singly, and having an interior swinging partition or leaf to prevent or reduce the liability of the matches crossing or fouling one another, said partition movable from side to side of said discharge orifice, to co-operate with the side wall of the match-safe to form a discharge chute for the matches.

4. A closed pocket match-safe having at one end an aperture for discharging matches singly, and having an interior swinging partition hinged at one edge, said partition at its free edge extending to said aperture and preventing the matches from crossing or fouling one another, said free edge of the partition extending close to the wall of the match-safe and co-operative with said wall to form a chute directing the matches into said aperture.

5. A closed pocket match-safe provided at one end with a discharge orifice and having an interior match-guiding partition in the vicinity of said orifice, said match-safe having at its other end a match-striking surface, and also having a cover provided with an opening through which said match-striking surface is exposed, said cover capable of clamping a match-igniting strip over said other end, to be accessible through said opening.

6. In combination, a match-box and an ignition strip, said match-box provided with a cover for holding the ignition strip down upon the end of the match-box, said cover having an opening to give access to the strip for striking a match thereon, said box comprising a magazine portion in which a supply of the strip is confined.

7. In combination, a match-box and an ignition strip, said match-box provided with a

- cover for holding the ignition strip down upon the end of the match-box, said cover having an opening to give access to the strip for striking a match thereon, said box comprising a magazine portion in which a supply of the strip is confined, said magazine being at one side edge of the box and divided by a partition from the match-containing portion of the box.
10. 8. In combination, a match-box and an ignition strip, said match-box provided with a cover for holding the ignition strip down upon the end of the match-box, said cover having an opening to give access to the strip for striking a match thereon, said box comprising a magazine portion in which a supply of the strip is confined, said magazine being at one side edge of the box and divided by a partition from the match-containing portion of the box, said strip magazine extending the height of the match-box, and the strip therein being zigzag-folded, the end of the outer layer of said zigzag strip being carried out through an aperture in the box and held down on the top of the match-box by means of said cover.
9. In combination, a match-box and an ignition strip, said match-box provided with a cover for holding the ignition strip down upon the end of the match-box, said cover having an opening to give access to the strip for striking a match thereon, said box comprising a magazine portion in which a supply of the strip is confined, said magazine being at one side edge of the box and divided by a partition from the match-containing portion of the box, said strip magazine extending the height of the match-box, and the strip therein being zigzag-folded, the end of the outer layer of said zigzag strip being carried out through an aperture in the box and held down on the top of the match-box by means of said cover, provision being made for preventing the zigzag folds from rising bodily from the magazine when the end of the strip is pulled up.
10. A closed match-safe having at one end an orifice for discharging matches singly, and formed with a discharge chute leading to said orifice, and provided with an internal separator adjacent to said orifice, said safe being provided at its bottom with a cover or lid containing said discharge orifice, whereby said lid may be opened for the introduction of matches into the safe, and having at its other end an apertured lid to hold down an ignition strip upon the end of the safe.
11. A closed match-safe having at one end an orifice for discharging matches singly, and formed with a discharge chute leading to said orifice, and provided with an internal separator adjacent to said orifice, said safe being provided at its bottom with a cover or lid containing said discharge orifice, whereby said lid may be opened for the introduction of matches into the safe, and having at its other end an apertured lid to hold down an ignition strip upon the end of the safe.
12. A closed pocket match-safe having at one end an aperture for discharging matches singly, and having an interior swinging partition or leaf to prevent or reduce the liability of the matches crossing or fouling one another, said leaf being formed at its bottom edge or portion with left-hand and right-hand guiding channels for the matches to be ejected.
13. A closed pocket match-safe having at one end an aperture for discharging matches singly, and having an interior swinging partition or leaf to prevent or reduce the liability of the matches crossing or fouling one another, said leaf being formed at its bottom edge or portion with left-hand and right-hand guiding channels for the matches to be ejected, means being provided to limit the swinging of the leaf so that either one channel or the other will be substantially coincident with the discharge aperture in the match-safe when the leaf is at either extreme end of its swing.
14. A pocket closed match-safe comprising a tubular body, a metal lining for said body, said lining having a partition pivoted thereto, said lining projecting at its lower end below the body, and a pivoted lid fitting over the projecting end of the lining and closing the bottom of the safe and having a discharge orifice to co-operate with said partition in discharging the matches.
15. A pocket closed match-safe comprising a tubular body, a metal lining for said body, said lining having a partition pivoted thereto, said lining projecting at its lower end below the body, and a pivoted lid fitting over the projecting end of the lining and closing the bottom of the safe and having a discharge orifice to co-operate with said partition in discharging the matches, said tubular body being of fine metal and said lining of inferior metal.
16. A pocket closed match-safe comprising a tubular body, a metal lining for said body, said lining having a partition pivoted thereto, said lining projecting at its lower end below the body, a pivoted lid fitting over the projecting end of the lining and closing the bottom of the safe and having a discharge orifice to co-operate with said partition in discharging the matches, an end inserted in the other end of said safe to close the same, a lid pivoted upon the closed end of the safe, a folded ignition strip inserted within said lining member, means forming a chamber or magazine in which said strip is confined, and a top lid pivoted to the safe and capable of holding the strip down upon

the upper end of the safe, said top lid being apertured to permit striking the matches upon the ignition strip.

17. A pocket closed match-safe comprising a tubular body, a metal lining for said body, said lining having a partition pivoted thereto, said lining projecting at its lower end below the body, a pivoted lid fitting over the projecting end of the lining and closing the bottom of the safe and having a discharge orifice to co-operate with said partition in discharging the matches, an end inserted in the other end of said safe to close the same, a lid pivoted upon the closed end of the safe, a folded ignition strip inserted within said lining member, means forming a chamber or magazine in which said strip is confined, and a top lid pivoted to the safe and capable of holding the strip down upon the upper end of the safe, said top lid being apertured to permit striking the matches upon the ignition strip, and said end of the safe being roughened for the striking of ordinary matches thereon when the ignition strip is removed therefrom.

18. A pocket closed match-safe comprising a tubular body, a metal lining for said body, said lining having a partition pivoted thereto, said lining projecting at its lower end below the body, a pivoted lid fitting over the projecting end of the lining and closing the bottom of the safe and having a discharge orifice to co-operate with said partition in discharging the matches, an end inserted in the other end of said safe to close the same, a lid pivoted upon the closed end of the safe, a folded ignition strip inserted within said lining member, means forming a chamber or magazine in which said strip is confined, and a top lid pivoted to the safe and capable of holding the strip down upon the upper end of the safe, said top lid being apertured to permit striking the matches upon the ignition strip, said closed end having an aperture out through which the ignition strip may be drawn.

19. A pocket closed match-safe comprising a tubular body, a metal lining for said body, said lining having a partition pivoted thereto, said lining projecting at its lower end below the body, a pivoted lid fitting over the projecting end of the lining and closing the bottom of the safe and having a discharge orifice to co-operate with said partition in discharging the matches, an end inserted in the other end of said safe to close

the same, a lid pivoted upon the closed end of the safe, a folded ignition strip inserted within said lining member, means forming a chamber or magazine in which said strip is confined, and a top lid pivoted to the safe and capable of holding the strip down upon the upper end of the safe, said top lid being apertured to permit striking the matches upon the ignition strip, said closed end having an aperture out through which the ignition strip may be drawn, and being provided at said aperture with a tongue to constitute the top of the magazine and to catch the folds of the ignition strip and prevent them from being drawn up out of the chamber when the strip is being pulled up to expose a fresh portion thereof for use.

20. A pocket closed match-safe comprising a tubular body, a metal lining for said body, said lining having a partition pivoted thereto, said lining projecting at its lower end below the body, a pivoted lid fitting over the projecting end of the lining and closing the bottom of the safe and having a discharge orifice to co-operate with said partition in discharging the matches, an end inserted in the other end of said safe to close the same, a lid pivoted upon the closed end of the safe, a folded ignition strip inserted within said lining member, means forming a chamber or magazine in which said strip is confined, and a top lid pivoted to the safe and capable of holding the strip down upon the upper end of the safe, said top lid being apertured to permit striking the matches upon the ignition strip, said closed end having an aperture out through which the ignition strip may be drawn, and being provided at said aperture with a tongue to constitute the top of the magazine and to catch the folds of the ignition strip and prevent them from being drawn up out of the chamber when the strip is being pulled up to expose a fresh portion thereof for use, said chamber having an inner wall to divide it from the main match receiver of the match-safe, said inner wall fixed at its upper end and yieldable laterally at its lower end to open the magazine for the introduction of the folded strip at said lower end of the magazine.
